US00D740791S

(12) **United States Design Patent**
Fujioka

(10) **Patent No.:** **US D740,791 S**
(45) **Date of Patent:** **** Oct. 13, 2015**

(54) **SILICONE SPEAKER MOUNTING
ACCESSORY**

(71) Applicant: **Robb Fujioka**, Manhattan Beach, CA
(US)

(72) Inventor: **Robb Fujioka**, Manhattan Beach, CA
(US)

(73) Assignee: **Fuhu, Inc.**, El Segundo, CA (US)

(**) Term: **14 Years**

(21) Appl. No.: **29/488,474**

(22) Filed: **Apr. 18, 2014**

(51) LOC (10) Cl. **14-01**

(52) U.S. Cl.

USPC **D14/224**
